UNITED STATES PATENT OFFICE.

RAYMOND A. SMITH, OF PHILADELPHIA, PENNSYLVANIA.

SAFETY DEVICE FOR DELIVERY OF MILK AND OTHER ARTICLES.

1,391,801.

Specification of Letters Patent. Patented Sept. 27, 1921.

Application filed April 11, 1921. Serial No. 460,257.

To all whom it may concern:

Be it known that I, RAYMOND A. SMITH, a citizen of the United States, residing at Philadelphia, in the county of Philadelphia, 5 State of Pennsylvania, have invented certain new and useful Improvements in Safety Devices for Delivery of Milk and other Articles, of which the following is a description, reference being had to the accompanying drawing and to the figures of reference marked thereon.

My invention relates to an improved device for insuring the safety of milk and other articles daily delivered to householders at hours when residents are not usually awake and stirring; the object being to provide, in connection with a door, a swinging section constructed so as not to disfigure the door, and having retaining means for the 20 milk or other articles to be delivered, which section, when the articles are placed in position thereon, may be swung inwardly and automatically locked against theft or exposure to the open air.

25 The invention consists in the matters hereinafter described and referred to in the appended claims.

In the accompanying drawings, which illustrate the invention—

30 Figure 1 is a front elevation of a portion of a house door, showing my invention applied thereto;

Fig. 2 is a sectional view on the line 2—2 of Fig. 1, looking in the direction of the 35 arrows;

Fig. 3 is a similar view on line 3—3 of Fig. 1; and

40 Figure 4 is a view similar to Fig. 1, showing a modification of my invention.

45 In these drawings, 1 represents a portion of the door of a house. A section of the lower part thereof is removed and my invention applied thereto. This consists of a panel 2 formed of any suitable material,

preferably of the same wood of which the door is constructed, and is bordered with brass molding strips, or other suitable strips

3, to give an ornamental appearance. It is provided with a transverse shelf 4, project-

50 ing from its lower face to afford a support for the milk bottles or other containers to be placed thereon, and at its upper portion

has a transversely projecting rack 5 formed of wire or strap metal to partially embrace 55 the necks of the bottles or upper portions of the containers. The ends of this strap or

guard are fastened by rivets or bolts or screws 6 to the molding for the panel.

A vertical rod or shaft 7 is journaled in the upper and lower faces of the cut-out portions of the door in bearings 8 and 9, and passes through the panel 2 at its central portion, forming a vertical shaft on which the panel may rotate.

A safety catch or lock 10 is provided on 65 the face of the panel with suitable keepers 11 for the bolts on the adjacent portion of the door on opposite external and internal faces of the door. Keys are provided for the catch or lock, of which duplicates are 70 held by the householder, and by the delivery man, to prevent unauthorized tampering. This is not necessary, however, as the catch may be the ordinary spring bolt, without key, but the householder may have a key, 75 so that when the delivery man has delivered the articles and swung the panel inside and the inside catch has locked, the panel can not be swung outwardly, by prying open the lock from the outside, but must be un- 80 locked and released from the inside.

In Fig. 4, a modification of the structure is shown, in which two swinging panels are provided, one for the reception of milk containers, and the other modified for the reception of containers for bread, rolls or other articles. The construction and mode of operation of these swinging panels is the same as for the single one, above described.

The invention is used in the following 90 manner: The delivery man places the bottles of milk on the shelf projecting from the panel, and unlocks the external catch, if a key catch, or releases it, if an ordinary spring latch, and swings the panel on its 95 pivot, turning the shelf rack and bottles held thereby to the inside of the house or vestibule. When swung around 180°, the safety catch engages the inside keeper and can only be released and swung outwardly again by 100 the householder.

It will be seen that my invention not only provides for the security of the delivered articles from theft, but also security from exposure to weather, germs, or contact with 105 anything unsanitary, the article on delivery being at once delivered to the interior of the house.

Many modifications and changes in the details of construction of the invention may 110 be made without departing from the spirit thereof.

Having thus described my invention, what I claim as new and desire to secure by Letters Patent, is:

1. A device for delivering articles to houses, comprising a door section or panel, provided with means for supporting the articles, said section or panel being centrally pivoted to swing on a vertical axis, the panel and adjacent door sections being provided with coöperating safety catches.
2. A device for delivering articles to houses, comprising a door section or panel, provided with means for supporting the articles, said section or panel being centrally pivoted to swing on a vertical axis, a safety catch on the panel coöperating with an external keeper on the adjacent door section, and a coöperating internal keeper on the opposite door section, whereby when the articles are placed on the panel, and the safety catch released, the panel may be swung inwardly and automatically locked on the inside and only releasable by manipulation from within.

3. The herein described safety device for 25 delivery of articles, comprising a panel or section pivotally attached to a door by a central vertical pivot, a shelf on said panel for supporting the base of articles, a rack for holding the upper ends of said articles, 30 a safety catch on one edge of the panel, and external keeper on the adjacent door portion, coöperating with said safety catch, and an internal keeper on the opposite adjacent door section to coöperate with the safety 35 catch in another portion of the panel.

4. The panel having the projecting shelf and rack, a door section, a vertical shaft on which the panel is centrally swung, said shaft journaled in upper and lower bearings on the door section, a safety catch on the panel and external and internal oppositely arranged keepers coöperating with the safety catch in alternate positions of the panel.

In testimony whereof, I affix my signature.

RAYMOND A. SMITH.
